ATTORNEY.

UNITED STATES PATENT OFFICE.

WILLIAM T. HATMAKER, OF DAYTON, OHIO, ASSIGNOR TO THE HUFFMAN RECORDING PUMP COMPANY, OF DAYTON, OHIO, A CORPORATION OF OHIO.

LIQUID-DISPENSING PUMP.

1,352,664.

Specification of Letters Patent. Patented Sept. 14, 1920.

Continuation of application filed February 27, 1919, Serial No. 279,491. This application filed September 8, 1919. Serial No. 322,249.

To all whom it may concern:

Be it known that I, WILLIAM T. HATMAKER, a citizen of the United States, residing at Dayton, in the county of Montgomery and State of Ohio, have invented certain new and useful Improvements in Liquid-Dispensing Pumps, of which the following is a specification, reference being had thereto to the accompanying drawing.

10 This invention relates to liquid dispensing pumps and is a continuation of the application filed by me February 27, 1919, Serial No. 279,491, as to all matter common to the two applications.

15 In the operation of dispensing pumps in which the operating device moves in one direction only, as is the case in the above mentioned application, difficulty is sometimes encountered, due to the fact that the quantity 20 of liquid required by a customer may involve the delivery of less than a full measure. For example, where the pump cylinder discharges one gallon upon each full operation of the piston a customer may require seven 25 and one-half gallons, and where this happens the piston remains in an intermediate position at the end of the discharge operation and it is necessary either to discharge and dispose of, in some manner, the liquid that remains in the cylinder above the piston, or 30 to include this part of a measure in the order of the next customer. Either method is unsatisfactory. If the first is followed, it is necessary to discharge the liquid into a separate receptacle and eventually return it to the tank, and, if the second method is followed, confusion is very liable to be the result.

35 The object of the invention is to provide, in a pump of this kind, means for returning the undischarged portion of liquid remaining in the cylinder, after a partial operation of the piston, to the cylinder on the intake side of the piston.

40 A further object of the invention is to provide, in a pump of this kind, means for rendering the registering mechanism inoperative during the operation of the pump to return this undischarged portion of the 45 liquid to the cylinder on the intake side of the piston.

Figure 1 is a front elevation, partly broken away, of a dispensing pump embodying my invention; Fig. 2 is a side elevation, 50 partly broken away, of such a pump; Fig. 3

is a transverse sectional view taken through the cylinders immediately above the base; Fig. 4 is a transverse sectional view, partly broken away, taken through the valve casting on the cylinder head; and Fig. 5 is a detail view of the register operating mechanism.

In these drawings I have shown the invention as embodied in a double cylinder pump, similar to that shown and described in the above mentioned application, but it will be understood that this particular type of pump is chosen for the purpose of illustration only, and that the invention may be applied to pumps of various kinds, either 60 single cylinder or double cylinder pumps.

The pump here illustrated comprises two cylinders 1 and 2, each of which preferably has a capacity of one gallon. Mounted in each of these cylinders is a valved piston 3, 65 the valve 4 of which is so arranged that it will be seated upon the discharge stroke and will be opened upon the return stroke of the piston to permit the cylinder above the piston to again fill with liquid. Each piston 70 has connected therewith a piston rod 5, extending beyond the end of the cylinder, and having connected therewith a rack 6, the two racks meshing with the opposite sides of an operating gear 7. This gear is rotated first in one direction and then in the other to alternately raise and lower the respective pistons by means of a suitable actuating device, which, in the present instance, comprises a crank 8 secured to an 75 operating shaft 9^a and connected through suitable gearing with the operating gear 7. The connections between the shaft and the operating gear are such that the direction of movement of the gear may be reversed without reversing the direction of movement of the crank. This operating mechanism is 80 fully described in the above mentioned application and, inasmuch as it forms no part of the present invention, it need not be here 85 described in detail.

The lower ends of the two cylinders communicate, through a suitable supply line, with a tank, or other source of liquid supply, which is usually under ground. In the 90 present construction the two cylinders are seated on a single base casting, which is provided with two passageways 9 and 10 communicating respectively with the lower ends 95 of the cylinders 1 and 2, and each of the pas- 100 105 110

2

sageways communicates with a conduit 11, which, in turn, is connected by a pipe 12 with the source of supply. The communication between the conduit 11 and each passage 5 sageway 9 and 10 is controlled by a check valve 13, which will open to permit the flow of liquid to the respective cylinders upon the upward stroke of the piston and will close, to prevent the escape of the liquid, upon the 10 downward stroke of the piston. The upper, or discharge ends, of the cylinders, are preferably connected with a single discharge pipe, and in the present construction, a single head casting 14 is provided to receive the upper ends of both cylinders, and this head casting has a transverse passageway 15 communicating with the discharge 15 ends of both cylinders and connected with the discharge pipe 16.

In order that the undischarged portion 20 of a measure of liquid may be returned to the cylinder on the intake side of the piston, when the delivery has been completed with the piston in intermediate position, I have provided a by-pass, or conduit, 17, leading from the discharge end of the cylinder to the intake end thereof and have provided means for controlling this by-pass. In a 25 double cylinder pump, such as is here shown, I prefer to use a single by-pass for both cylinders and this is very easily accomplished in the present instance by connecting the same with the passageway 15 in the head casting, which passageway communicates with both 30 cylinders. The by-pass may be connected with the intake end of the cylinder either directly or through a part of the supply line and in the case of the double cylinder pump here shown I prefer to connect the lower end 35 of the by-pass with the conduit 11, as in this manner it may be connected, through the check valves 13, with either cylinder. The by-pass may be connected with the cylinders, or head casting, 15, in any suitable manner, 40 but, in the present instance, I have connected the by-pass with the head casting through the opening leading to the discharge pipe. To this end the discharge opening leads into the casing 18 of a controlling valve, which 45 casing is provided with a port 19 for the discharge pipe and a port 20 for the by-pass. Mounted in said casing is a suitable three-way valve 21, which is here shown in the form of a rotary plug valve having an axial 50 opening in line with the discharge opening of the head casting and having outlet ports to connect the axial opening with either the port 19 of the discharge line, or the port 20 of the by-pass. The openings, or ports, 55 in the valve member are so arranged that the valve may be set in an intermediate position in which both the by-pass and the discharge line will be cut off from the cylinders, and the pistons in the cylinders consequently 60 locked against movement. The discharge 65

opening and valve casing may be arranged in any suitable position with relation to the head casting, but, as a matter of convenience, I have here shown them arranged centrally of the casting with the stem 22 of the valve 21 extending vertically above the casting 18. It will be apparent, therefore, that when the operator has completed the delivery of the required amount of liquid before the piston has completed its discharge movement, he will interrupt the movement of the operating device, or crank, and adjust the valve 21 to disconnect the cylinder from the discharge pipe and connect it with the by-pass, and will then further operate the crank 75 to complete the movement of the piston, the liquid from the cylinder passing through the by-pass to the supply line and thence again to the cylinder.

I have also provided means for rendering 80 the registering device inoperative and thus preserving an accurate record of the liquid actually delivered to customers. The registering device may take various forms and may be operated in different ways, but, in the present machine, it comprises a dial 23 having thereon figures representing the 85 number of gallons delivered and the cost of each quantity delivered. Traveling over this dial is a pointer 24 which is operatively connected with the operating mechanism for the pump. To this end the pointer is rotatably mounted on a shaft 25 and has connected therewith a ratchet wheel 26 with which cooperates a pawl 27 carried by an arm 28 loosely mounted on the shaft 25 for movement relatively to the ratchet wheel and the pointer. The arm 28 is connected, by means of a rod 29, to an arm 30 pivotally mounted on a fixed part of the supporting frame and arranged to be actuated by a cam 31, which is connected with the operating gear 7. This cam is so shaped that it will impart, to the arm 30, and consequently to the pawl 27, sufficient movement to advance the pointer through one full indication on the dial for each complete movement of the piston of either cylinder. Inasmuch as the cylinders in the present instance contain one gallon each, 100 each complete movement of the pointer represents one gallon. However, the cam 31 is so shaped and the pawl and ratchet 27 and 26 are of such a character that this movement will be imparted to the pointer in four 105 equal parts, each part representing one quart. To prevent the operation of this registering device when the cylinder is discharging to the by-pass I have provided means for rendering the pawl 27 inoperative 110 and this means is preferably so connected with the valve which controls the by-pass that the pawl will be automatically rendered operative or inoperative when the valve is shifted. To this end I have con- 115

120

125

130

nected with the rod 29, which actuates the pawl 27, a rod 32, the lower end of which is slidably mounted in a guideway 33 and bears against a cam 34 connected with the 5 rotatable member of the valve and, in the present instance, formed integral with a handle 35 mounted on the valve stem 22. The arrangement of the cam is such that when the handle 35 is actuated to connect 10 the by-pass with the cylinder, the pawl will be lifted into, and retained in, its elevated position, thus rendering the registering mechanism inoperative, and will remain in this position until the valve is returned to 15 its normal position, that is, the position in which the discharge pipe is connected with the cylinder.

While I have described this mechanism as applied to a registering device, it will be 20 obvious that it may be utilized for rendering inoperative either a registering device or a recording device, or both.

While I have shown one embodiment of 25 my invention, I wish it to be understood that I do not desire to be limited to the details thereof, as various modifications may occur to a person skilled in the art.

Having now fully described my invention 30 what I claim as new and desire to secure by Letters Patent, is:

1. In a liquid dispensing apparatus, a cylinder having a discharge opening at one end, a piston mounted in said cylinder, a conduit to connect said discharge opening 35 with said cylinder on the intake side of said piston, and thereby permit the liquid remaining in the cylinder after an incomplete stroke of the piston, to be returned to the intake end of the cylinder, and means to control 40 the passage of liquid through said conduit.

2. In a liquid dispensing apparatus, a cylinder, a piston mounted in said cylinder, a discharge conduit for said cylinder, a conduit to connect the discharge end of said cylinder with the intake end thereof and thereby permit the liquid remaining in the cylinder after an incomplete stroke of the piston to be returned to the intake end of 50 the cylinder, and means to connect said discharge end of said cylinder with the last mentioned conduit and to disconnect said cylinder from the first mentioned conduit.

3. In a liquid dispensing apparatus, a cylinder having a discharge conduit, a piston in said cylinder, a discharge conduit adapted to be connected with said discharge opening to connect the discharge end of said cylinder with the intake end thereof, and thereby permit the liquid remaining in the cylinder after an incomplete stroke of the piston to be returned to the intake end of the cylinder, and a valve to connect either 60 of said conduits with said discharge opening.

4. In a liquid dispensing pump, two cylin-

ders, a discharge conduit for said cylinders, a piston mounted in each of said cylinders, a conduit adapted to connect the discharge end of either of said cylinders with the intake end thereof, and means to disconnect 70 said cylinders from the discharge conduit and to connect one of said cylinders with the second mentioned conduit.

5. In a liquid dispensing pump, two cylinders, a piston mounted in each cylinder, a 75 single outlet opening for both cylinders, a supply line leading to both cylinders, a conduit connected with said supply line, and means for connecting said conduit with said discharge opening.

6. In a liquid dispensing apparatus, two cylinders, a supply line communicating with both of said cylinders, a single head for closing the discharge ends of both of said cylinders, said head having a discharge opening communicating with both cylinders, a discharge conduit adapted to be connected with said discharge opening, a second conduit adapted to be connected with said discharge opening and leading to said supply 90 line, and means to connect either of said conduits with said discharge opening.

7. In a liquid dispensing apparatus, two cylinders, a supply line communicating with the intake ends of both cylinders, a head for 95 closing the discharge ends of said cylinders, said head having a discharge opening communicating with both cylinders, a valve casing communicating with said discharge opening, a discharge conduit connected with 100 said valve casing, and a second conduit connected with said valve casing and leading to said supply line, and a valve member mounted in said casing and operable to connect said discharge opening with either of said 105 conduits.

8. In a liquid dispensing apparatus, a cylinder, a piston mounted in said cylinder, a conduit adapted to be connected with the discharge end of said cylinder to connect 110 the same with the intake end thereof, means for connecting said conduit with the discharge end of said cylinder, a registering device to register the operations of said piston, and means for rendering said registering 115 device inoperative when said conduit is connected with the discharge end of said cylinder.

9. In a liquid dispensing apparatus, a cylinder, a piston mounted in said cylinder, a 120 conduit to connect the discharge end of said cylinder with the intake end thereof, a valve to control said conduit, a registering device to register the operations of said piston, means actuated by said valve to render said 125 registering device inoperative when said valve is actuated to connect the discharge end of said cylinder with the intake end thereof.

10. In a liquid dispensing apparatus, a 130

- cylinder, a piston mounted therein, a conduit to connect the discharge end of said cylinder with the intake end thereof, a valve to control said conduit, a registering device to register the operations of said piston and comprising pawl and ratchet operating mechanism, and an operative connection between said pawl and said valve to cause the pawl to be moved into an inoperative position when said valve is actuated to connect the discharge end of said cylinder with the intake end thereof.
11. In a liquid dispensing apparatus, a cylinder, a piston mounted in said cylinder, a conduit to connect the discharge end of said cylinder with the intake end thereof, a valve to control said conduit, a registering device to register the operations of said piston, a cam operatively connected with said valve, and means actuated by said cam to render said registering mechanism inoperative when said valve is actuated to connect the discharge end of said cylinder with the intake end thereof.
12. In a liquid dispensing apparatus, two cylinders, pistons mounted in said cylinders, a supply line leading to the intake ends of said cylinders, a head to close the discharge ends of both of said cylinders and having a discharge opening communicating with both cylinders, a valve casing mounted on said head in communication with said discharge opening, a discharge conduit connected with said valve casing, a second conduit connected with said valve casing and leading to said supply line, a valve member mounted in said casing to connect said discharge opening with either of said conduits, registering mechanism to register the operations of both of said pistons and comprising an operating pawl, a handle for actuating said valve member, a cam connected with said handle, and a part arranged to be actuated by said cam to move said pawl into an inoperative position when said valve member is actuated to connect said discharge opening with said supply line.

In testimony whereof, I affix my signature hereto.

WILLIAM T. HATMAKER.
